WEFT INSERTING MECHANISM FOR LOOMS

William Felton, Bradford Moor, Bradford, England, assignor to David Crabtree and Son Limited, Bradford, England, an English company

Application March 9, 1937, Serial No. 129,834
In Great Britain March 15, 1936

5 Claims. (Cl. 139—123)

This invention relates to weft inserting mechanism of looms in which a reciprocating needle carries said weft in folded form between the warp threads from one side to the other of same. 5 Thus said weft travels from its source of supply forward through the warp at twice the speed of the inserting needle, therefore making the advancing motion of the weft double the speed of the weft supplying needle. This causes such 10 jerky action to the weft that it often breaks and causes great delay in the process of weaving. To avoid this I make use of mechanism that will enable the receding motion of the needle to be used to commence the withdrawal of weft from the 15 source of supply immediately the previously supplied weft has been fixed by its advancing folded end being secured to the warp threads at the edges of the woven fabric. Thus both the advancing and the returning of the operating needle 20 and its mechanism secure the continued withdrawal of the weft from its source of supply (such as from a bundle or cone of coiled thread). To enable this I cause this withdrawal of the weft by the receding actions of the spindle to be accumulated and then paid out under such conditions 25 that said paying out may continue until the full advancing motion of the spindle has been completed without any intermission except momentarily at the times of the changes of direction. 30 To clearly describe my invention reference is made in the accompanying sheets of drawings which are illustrative thereof, in which:

Fig. 1 is a front elevation of sufficient of the frame-work and operating mechanism of a loom 35 of the type known as a gripper pile or pile-forming loom as to illustrate the application thereto of our invention.

Fig. 2 is an end elevation of the parts shown by Fig. 1 as seen looking from right to left of said 40 figure.

Fig. 3 is a plan of the parts shown by Fig. 1.

Figs. 4 and 5 are diagrammatical representations 45 of the devices shown by Figs. 1 to 3 inclusive but with certain of the parts in their altered positions, as is hereinafter described.

Figs. 6 and 7 are similar diagrammatical illustrations of a modification of the devices for attaining the same object with the alterations hereinafter explained.

To attain the object of my invention I add or insert an additional guide-eye 2 which is arranged to be operated through a path half the length of the path traversed by the needle 3 and 55 by mechanism working in unison with the mo-

tions of the needle 3 but at a slower speed, as is hereinbefore stated.

This guide-eye 2, carried by its sliding bracket 2b, is in its extreme rearward position when the eye 2a in the needle 3 is also in its rearward position with its eye 2a at its outer end ready for entering the shed of the warp as shown by Fig. 5.

The weft thread 5 which extends through the eye 2a of the needle 3 (to be thereby inserted into the shed of warp threads 6) is withdrawn 10 from its source of supply 7 to travel in the direction of the arrow a, and at the first insertion of the doubled strands of weft has its loose end held by any of the usual devices from entering said shed.

When the needle advances to project a loop of 15 weft yarn through the shed, it pays out yarn as it goes along at the same rate as the rate of its progress through the shed, yarn leading from the source of supply 7 being drawn into the shed as 20 the needle advances. This supply yarn must overtake the needle-eye 2a at the same rate as the speed of advance of the eye. Hence the yarn is drawn into the shed at twice the speed of the advance of the needle. During the retractive 25 movement of the needle, the loop of yarn remains stationary in the shed, but, owing to the movement of the needle relative thereto, the yarn slides through the eye at the same rate as the speed of movement of the needle. If the supply yarn were 30 lead directly to the needle from the source of supply, the yarn would be drawn from the source at a rate equal to twice the speed of advance of the needle while the needle was moving into the shed and would not be drawn at all during the 35 retractive movement of the needle. According to the present invention, a take-up mechanism is provided to draw yarn from the supply 7 at a rate substantially equal to the rate of travel of the needle, no matter in which direction the 40 needle is moving.

In the arrangement of the apparatus for giving the equal feed in length of the weft during the receding motion of the needle with that of the advancing motion of the needle for the purpose 45 stated I make use of means for causing the thread guide 2 to recede and advance at one half the speed of the thread guide 4, and this I effect by securing the thread guide 2 on a bracket 2b which is reciprocated upon the slide w by being 50 fixed to a belt or cord 8 which encircles a driving pulley 9 that is operated by a pinion 10 which is rotated forward and backward by a toothed quadrant 11, a lever 12 and crank 13 (Figures 4 and 5). The said crank 13 is mounted to revolve with a 55

shaft operated by one or other driving shafts of the loom so that said crank is carried through one complete revolution during each of the advancing and receding motions of the needle 3, and such driving cord 8 (as is shown by the drawings) is made to travel over the guide pulleys 15 and 15a to operate the bracket 2b in an even path along the guide-way w.

In like manner the advancing and receding of the needle 3 is effected by another cord or belt 16 which is made to take around the driving pulley 17 so that by said driving pulley 17 being fixed upon the spindle of the pinion 10 (which is operated by the quadrant 11) said cords or belts 15 and 16 will always work in unison or simultaneously in the same directions.

This belt or cord 16 is secured to the bracket 4a and is made to travel over the guide pulleys 18 and 18a.

20 By the length of the periphery of the cord or belt driving wheel 9 being only half the length of the periphery of the pulley 17 around which the belt 16 takes (in order to be thereby driven) it will be seen that the advancing motions of the 25 needle 3, its guide-eye 4 and the bracket 2b (with its guide-eye 2) will always be in the same direction as each other and that the guide eye 2 will be carried by the bracket 2b through half the distance that the guide-eye 4 is carried.

30 In the arrangement of the devices shown by Figs. 1 and 2 of the drawings (the operations of which are the same as those shown by Figs. 4 and 5) it will be observed that I am enabled to mount the shaft of the driving pinion 10 with its 35 pulleys 9 and 17 upon the rail 20 of the framework of the machine which may be of an ordinary construction, and this framework couples the end frame 21 of the loom to the outermost end frame 22 which will carry the pulley 18 around 40 which the driving cord or belt 16 travels. Thus said driving cord or belt 16 will operate the bracket 4a, while the cord or belt which takes around the pulley 9 and the guide pulleys 15 and 15a may have bearings for said guide pulleys 15 and 45 15a formed by an extension 21a from the end frame 21 of the loom and by a vertical bar 23 extending from the rail 20 and an additional rail 24 which forms the guide way for the bracket 4a. The bar 23 and the extension 21a may act as supports for the guide bar w on which the bracket 50 2b travels, the other parts of the operating mechanism being common and well understood.

As an alternative method whereby I can secure the withdrawal of the length of weft from the 55 supply, half by the advancing motion of the needle and the other half by the receding motion of the needle (in each case such withdrawal being equal to the length of the needle), I may lead the weft yarn from the guide-eye 2 directly to the 60 eye of the needle 3, as indicated in Figures 6 and 7.

When the said guide-eye 4 carried by the needle 3 is dispensed with I now add an additional guide pulley 15b for the weft 5, and the weft in this case 65 is carried from the eye 2a of the needle 3 through the guide eye 2, back over the guide pulley 15b and reaches forward to the supply 7. Thus as all the other fittings are similar and operate similarly to those described by reference to Figs. 4 and 70 5 of the drawings, those devices now shown by Figs. 6 and 7 of the drawings only require the difference in their functions to show that they have the same effect as those herein first before described.

75 That is to say, as is shown by Fig. 6, the needle

3 is in its advanced position and therefore its guide-eye 2a with the weft passing through it is at the extreme edge of the fabric being woven, and the thread reaching therefrom to the guide-eye 2 will be held by the near edge of the fabric 5 close to the guiding pulley 15a and so will pass through the eye 2 and around the guiding pulley 15b to reach forward to the source of supply 7.

When the needle 3 commences to return, so also does the motion of the bracket 2b commence 10 the return of the guide-eye 2, and as it moves through half the length of the path through which the needle moves, but also at half the speed, it will drag, from the source of supply 7, sufficient length of weft to pass over the pulley 15 15b, around through the guide eye 2 and back to the rear edge of the woven fabric as much length of weft as the full receding action of the needle 3 will require where its eye 2a has reached its stationary position shown by Fig. 7 when said eye 20 recommences its forward movement to insert the double shot of weft through the warp as is hereinbefore described.

In this advancing from the position shown by Fig. 7 to again reach the position shown by Fig. 6, 25 the needle 3 will drag the weft 5 through the guide eye 2 around the pulley 15b at a rate that will equal the paying out rate of the moving guide eye 2 until said guide eye 2 reaches its position shown by Fig. 6. Thus the additional weft is paid 30 out (by the actions of the guide eye 2) to the advancing needle 3 at an equal rate to the pull of the weft by the guide-eye 2a as it advances. Thus the guide-eye 2 will supply half the length, while the other half of the length required by the 35 advancing of the needle is made available by the advance of the eye 2, this amount of weft having previously been drawn from the supply during the retractive stroke of the needle 3 and the 40 guide-eye 2.

Such being the object of my said invention, what I claim is:

1. In weft inserting mechanism of a loom of the type having a needle-weft-carrier, said needle being provided with an eye at its leading end for 45 guiding and carrying the weft, a weft guide mounted upon supports at the rear end of the needle, an additional guide-eye arranged to move at half the rate of speed of the needle and through half the distance, a bracket upon which the added guide-eye is fixed and with which it moves, and means for reciprocating in step the needle and the bracket upon which the weft carrying eye is fixed.

2. In weft inserting mechanism of a loom of 55 the type having a needle-weft-carrier, said needle being provided with an eye at its leading end for guiding and carrying the weft, an additional guide-eye mounted upon a sliding bracket, a guiding member forming a pathway over which 60 said bracket can slide, means for operating the bracket over the pathway through half the distance of the space which is traversed by the needle but moving said guide-eye at half the speed thereof, said means comprising a driving belt or cord travelling around a driving pulley and guide pulleys as same is operated by means herein described.

3. In weft inserting mechanism of a loom of the type having a needle-weft-carrier, said needle 70 having an eye for the weft near each end thereof, a bracket slidably mounted upon bearings providing a pathway over which it may slide, an additional guide-eye for the weft carried by said bracket, a driving belt or cord with pulley and 75

toothed quadrant operating devices for moving said bracket, a second driving pulley with belt or cord devices operated by the same toothed quadrant to transmit motion to the needle, and crank mechanism for operating said quadrant.

- 5 4. In a loom having a weft-inserting needle with an eye in its leading end, means for reciprocating said needle longitudinally, said means including a rock shaft and driving connections between said shaft and needle, an auxiliary guide-eye for the weft, and means for reciprocating said guide-eye in a path parallel to said needle simultaneously with movements of said needle but at
- 10

a lesser speed, said last-named means including said rock shaft and driving connections between said shaft and said guide-eye.

5 5. In a loom, a rock shaft, a pair of pulley wheels of different diameters mounted on said shaft, a longitudinally reciprocable weft-inserting needle, a driving belt operatively connecting said needle with the larger of said wheels, an auxiliary guide-eye for the weft reciprocable in a path parallel to said needle, and a driving belt 10 operatively connecting said guide-eye with the smaller of said wheels.

WILLIAM FELTON.
